INVENTOR.

Thomas J. Foster
BY
Harry L. Duncan

ATTORNEY.

UNITED STATES PATENT OFFICE.

THOMAS J. FOSTER, OF RIDGEWOOD, NEW JERSEY.

FLOOR CONSTRUCTION.

Application filed August 14, 1922. Serial No. 581,752.

To all whom it may concern:

Be it known that I, THOMAS J. FOSTER, a citizen of the United States, and resident of Ridgewood, Bergen County, State of New Jersey, have made a certain new and useful Invention Relating to Floor Constructions, of which the following is a specification taken in connection with the accompanying drawing, which forms part of the same.

This invention relates especially to floor constructions of a fire proof or semi-fire-proof character and aims to provide a light-weight water tight and sound-proof floor at a minimum cost.

In the accompanying drawing showing in a somewhat diagrammatic manner an illustrative embodiment of this invention.

Fig. 1 is a vertical sectional view of the construction, and

Fig. 2 is an enlarged section showing a modified form thereof.

The floor beams 1 are preferably of the skeleton or lattice web type in which the expanded webs may comprise the web diagonals 3 and these beams may be supported on or secured to the girders in any suitable way and spaced apart at distances of two or three feet more or less between centers. Combined ceiling and floor support strips or elements may be applied to these beams and sheets of sound and heat insulating non-combustible or fireproof material such as sheet rock, plaster board or other still more fireproof asbestos board mineral compositions may be used and may be cut in strips of such width as to extend between the centers of adjacent beams for example. These sheets or strips 8 are preferably supported on intermediate centering boards 7 during the construction of the floor panels and it is highly advantageous to support these centering boards on centering supports such as 4 which may extend through any suitable openings in these skeleton beam webs and thus have considerable length so as to more effectively insure the desired leveling up of this floor centering. For this purpose suitable wedges 5 which may have tapering lower faces co-operating with the upper or lower angles between the beam diagonals 3 may be driven or forced beneath these centering supports 4 of any suitable height and in some cases supporting blocks 6 may extend down to the lower beam flange and support these

wedges or the centering supports directly in some cases.

It is usually advantageous to apply a layer of water-proofing, sound-proofing material to the ceiling and floor support units and such waxy binder as minwax, for instance, may be applied thereto so as to give an effective layer 9 of this binder over the floor supports and in the cracks between the same before the cement or other floor composition is applied. Nailing strips such as 12 of wood or composition which may have the aligning or retaining nails 13 projecting therefrom may be put in place and effectively held down by this waxy binder especially if these nailing strips are put in place before the binder has cooled or solidified. These nailing strips may, if desired, be coated with this water-proof binder or otherwise water-proofed by appropriate treatment before being put in place in the floor structure. In some cases also clips such as 16 may extend at suitable distances up from the upper flanges 2 of the beams around which the lower portions 17 of these clips may be secured so as to support the expanded metal or other reenforcement 11 which may be used in these floor panels. The floor material 10 such as cement concrete or other suitable composition (hereinafter referred to indiscriminately as "cement," "composition," or "concrete") may be poured or cast into the panels and, if desired, leveled up in connection with the nailing strips 12 which may act as screeds in leveling this floor material 10 which adhesively engages the waxy binder so as to be thereby held in the desired position. A cement composition floor of this character two or three inches thick more or less is quite thoroughly fireproof when no nailing strips are used and even with the usual narrow nailing strips 12 the floor body is substantially fireproof and would practically prevent the penetration of fire up through the floor from the room below. As, shown in Fig. 2, these nailing strips may be used to secure in position the flooring boards 14 which may be nailed to these strips as by nails 15 at the desired intervals.

When the floor panels have set and hardened sufficiently the centering may be readily removed and for many purposes the skeleton or lattice web beams may be left in exposed position on the ceiling where they are much

less objectionable in appearance because of their light lattice or grille work appearance than ordinary steel beams would be. If desired, however, these floor beams of 5 skeleton web or other construction may be enclosed as shown in Fig. 2 and for this purpose metal or other casing members may be used to enclose and conceal the beams. Specially shaped blocking strips 18, 19 may 10 be secured adjacent the beam flanges in any suitable way and then the metallic or other beam casing 20, 21 may be nailed or otherwise secured in place as by the nails 23, 24 which may also secure the molding strips 22 15 next the ceiling thus producing the same effect as exposed wood beams in a beamed ceiling. If desired, however, the beams may be concealed by a hanging ceiling of fireproof or other construction and as shown 20 in Fig. 1, the supporting strips 25 may be secured to the beam flanges as by the wire ties 26 after the centering has been removed and then the plaster board or other composition material 27, preferably of non-inflammable or fireproof construction, may be 25 nailed or otherwise secured to these supporting strips so as to form a substantially continuous level ceiling, if desired.

This invention has been described in connection with a number of illustrative embodiments, forms, proportions, sizes, parts and methods of connection and use, to the details of which disclosure the invention is not of course to be limited since what is 30 claimed as new and what is desired to be secured by Letters Patent is set forth in the appended claims.

In the claims the word "beams" is used to describe rolled or fabricated beams or 40 joists, either made in one piece or built up of several pieces, such as are commonly used for floors for dwellings, apartments and office buildings; and the word "flange" is used to designate the top or bottom chord 45 member or members thereof.

I claim the following as my invention:—

1. The floor construction comprising beams having expanded webs adapted to accommodate and support centering elements 50 between the beams, non-combustible sheet rock ceiling and floor support sheets resting upon the upper flanges of said beams and extending between the adjacent beam flanges, a layer of waxy water-proofing sound- 55 proofing binder applied to said floor supports and between the joints thereof, nailing strips adhesively secured to said binder and concrete floor panels comprising metal reinforcement between said nailing strips and 60 adhesively secured to said binder.

2. The floor construction comprising beams having skeleton webs adapted to accommodate and support centering elements 65 between the beams, non-combustible ceiling and floor support sheets resting upon the up-

per flanges of said beams, a layer of waxy water-proofing, sound-proofing binder applied to said floor support, nailing strips adhesively secured to said binder and concrete floor panels comprising metal reinforcement 70 between said nailing strips and adhesively secured to said binder.

3. The floor construction comprising metal beams having skeleton webs adapted to accommodate centering elements between the beams, non-combustible ceiling and floor support sheets resting upon the upper flanges of said beams and extending between the beams, a layer of waxy sound-proofing, water-proofing applied to said floor supports, 75 nailing strips and interposed concrete floor panels above said water-proofing.

4. The floor construction comprising metal beams having webs, heat insulating non-combustible ceiling and floor support sheets 80 extending between the beams, a layer of water-proofing applied to said floor supports, nailing strips and interposed concrete floor panels above said water-proofing.

5. The floor construction comprising metal beams having expanded lattice webs adapted to accommodate and support centering elements between the beams, heat insulating non-combustible floor support sheets resting upon the upper flanges of said beams, concrete 90 floor panels comprising metal reinforcement above and adhesively secured to said floor support sheets and metallic beam casing members secured around the depending beams, blocking strips between said casing and beam flanges and molding strips between said beam casing and the adjacent ceiling sheets.

6. The heat and sound proof floor construction having beams spaced for directly supporting the floor slab and ceiling, floor slab supporting sheets comprising layers of sound proof material resting upon the tops of and insulating said beams, a continuous layer of concrete laid directly upon said floor slab 100 supports and constituting therewith a unitary floor slab, and ceiling supports attached to said beams and comprising layers of sound proof material forming a continuous insulation beneath said beams and adapted 110 to receive the ceiling finish.

7. The floor construction comprising beams having skeleton webs adapted to accommodate centering elements between the beams, floor support sheets of non-combustible mineral material supported from said beams and resting upon the upper flanges thereof, a layer of waxy water-proofing binder applied to said sheets, a flooring comprising cement concrete panels and wooden nailing strips adhesively secured to said binder, and beam casing members enclosing the depending portions of said beams.

8. The floor construction comprising beams having skeleton webs adapted to ac- 130

- commodate centering elements between the beams, floor support sheets supported from said beams, a layer of binder applied to said sheets, a flooring comprising cement concrete panels, and nailing strips adhesively secured to said binder, and members covering the depending portions of said beams.
9. The floor construction comprising fire-proof beams having skeleton webs adapted to accommodate and support centering elements between the beams, combined ceiling and floor support sheets of non-combustible material supported from said beams and resting upon the upper flanges thereof, a layer of waxy water-proofing, sound-proofing binder applied to said sheets and a flooring comprising concrete panels adhesively secured to said binder.
10. The floor construction comprising fire-proof beams, combined ceiling and floor support sheets supported from said beams, a layer of waxy water-proof, sound-proofing binder applied to said sheets and a flooring comprising concrete upon said layer.
11. The heat and sound proof floor construction comprising beams spaced for directly supporting the floor slab and ceiling, combined ceiling and floor slab supports in the form of sheets of plaster board or other laminated sound and heat insulating material arranged over and secured to said beams by ties, and a floor panel formed of concrete laid upon said sheets to embed said ties and constituting therewith an integral slab continuous across said beams for insulating them against transmitting heat and sounds to the ceiling beneath from the floor above and vice versa.
12. The heat and sound proof floor construction comprising beams spaced for directly supporting the floor slab and ceiling, combined ceiling members and floor slab supports in the form of sheets of plaster board or other laminated sound and heat insulating material, said sheets extending over the beams and insulating them from the slab, a self-supporting floor slab of non-combustible hardening plastic material secured to said sheets and continuous across said beams, forming a laminated protective load sustaining structure non-conductive to heat and sound completely insulating the ceiling beneath from the floor above and vice versa.
13. The floor construction comprising beams having skeleton webs, combined ceiling and floor support sheets of non-combustible mineral material supported from said beams and resting upon the upper flanges thereof, a layer of waxy waterproofing applied to said sheets and a flooring comprising cement concrete panels arranged above and adhesively secured to said waterproofing.
14. The floor construction comprising beams, combined ceiling and floor support sheets of heat insulating, non-combustible material supported from said beams, a layer of water-proofing applied to said sheets and a flooring comprising cement concrete panels arranged above said waterproofing, said combined ceiling and floor constituting a unitary rigid structure having smooth exposed surfaces.
15. The heat and sound proof floor construction comprising spaced flanged beams, heat and sound insulating sheets spanning the spaces between said beams and covering their top flanges, nailing strips bridging said beams and spaces and supported out of contact with the tops of said beams, and a layer of concrete supported on said sheets and embedding said nailing strips.
16. The heat and sound proof floor construction comprising spaced flanged beams, heat and sound insulating sheets spanning the spaces between said beams and covering their top flanges, clips for securing said sheets and beams together, the upper portions of said clips projecting above said sheets, nailing strips bridging said beams and spaces and supported out of contact with the tops of said beams, and a layer of concrete supported on said sheets and embedding said projecting clip portions and nailing strips.
17. The heat and sound proof floor construction comprising spaced flanged beams, heat and sound insulating sheets supported on the beam flanges and spanning the spaces between said beams, clips for securing said beams and sheets together, the upper portions of said clips projecting above said sheets, and a layer of concrete supported on said sheets above and out of contact with said beams and embedding said projecting clip portions, whereby said beams and concrete layer are securely connected and substantially insulated from each other.
18. The substantially fireproof and sound proof floor construction comprising steel beams spread at substantially uniform distances apart, floor supports of sheet-like insulating material extending in a substantially continuous layer over and between said beams, metal ties extending above said sheet-like insulating material, and a floor slab of cementitious material formed upon said floor supports and having said ties embedded therein.
19. The substantially fireproof and sound proof floor construction comprising steel beams spread at substantially uniform distances apart, floor supports of sheet-like insulating material extending in a substantially continuous layer over and between said beams, and a floor slab of cementitious material formed upon said floor supports.
